UNITED STATES PATENT OFFICE.

GEORGE E. PANCOAST, OF NEW YORK, N. Y.

PARCEL-DELIVERY SYSTEM.

SPECIFICATION forming part of Letters Patent No. 581,131, dated April 20, 1897.

Application filed June 11, 1896. Serial No. 595,157. (No model.)

To all whom it may concern:

Be it known that I, GEORGE E. PANCOAST, a citizen of the United States, and a resident of New York city, county of New York, and 5 State of New York, have invented certain new and useful Improvements in Parcel-Delivery Systems, of which the following is a specification, reference being had to the accompanying drawings, forming a part thereof, 10 in which similar letters of reference indicate corresponding parts.

This invention relates to an improved parcel-delivery system of the class especially adapted for handling bundles of newspapers, 15 the object of the invention being to provide a system of this character adaptable for transmitting bundles of papers or other matter from any given location to points remote therefrom, situated either upon a level or 20 varying elevations.

In carrying out the invention I employ a novel combination of parts, and especially a universal endless chain adaptable for carrying depending bundle-receptacles and for 25 traveling in any direction, whereby bundles may be taken on at one location and delivered at a remote distance therefrom at different elevations.

The invention will be hereinafter fully described, and specifically set forth in the annexed claims.

In the accompanying drawings, forming part of this specification, Figure 1 is a side elevation of my improved construction. Fig. 35 2 is a plan view thereof. Fig. 3 is a vertical sectional elevation taken on a line xx of Fig. 1. Fig. 4 is a side elevation of a portion of the construction. Fig. 5 is a vertical sectional elevation taken on a line yy of Fig. 4. Figs. 40 6 and 7 are detail views of depending receptacles for parcels adapted for use in my system. Fig. 8 is a vertical sectional elevation illustrating a means for driving the chain used in my system; and Fig. 9 is a side elevation of a portion of the system, illustrating a means for guiding the chain when it is traveling from one elevation to another.

In the practice of my invention I provide, primarily, an endless chain A. Said chain 50 comprises a plurality of hexagonal plates a and links a' for connecting them. Located at

regular distances upon the under surfaces of these said plates are depending lugs or arms a^2 , which said arms are adapted to carry depending parcel-receptacles B, which said receptacles are preferably made of a single piece of malleable sheet metal, and they comprise a depending arm b and branches b' , the outer ends of which branches are bent upwardly for forming the completed parcel-carrying receptacle, as clearly illustrated in Fig. 7 of the drawings. These said receptacles may be otherwise constructed, but the structure herein shown and described, being of a simple and inexpensive nature, is preferable. The 55 said chain A is extended around any suitable area of any desired contour. In the drawings I have illustrated an angular contour, and it is mounted, where it travels upon a straight line in a horizontal direction, upon beveled 60 rollers C, which said rollers are journaled in boxes d of hangers D. At points where the chain takes varying directions upon the same horizontal level the chain is mounted upon grooved rollers E, which said rollers are journaled upon the lower ends of depending hangers D'. To further support the chain at the points where its direction changes, angle-iron 65 bearings F are provided. These said bearings support the outer edges of the plates a and 70 prevent the chain from leaving the grooves e of the rollers E. These said bearings F are mounted upon hangers D².

At the points where the chain leaves a horizontal line for the purpose of reaching another elevation vertical rollers C' are provided, which said rollers bear against the lower surfaces of the plates a at the inner and outer edges thereof, whereby a sufficient space is left for the passage of the carriers B, as clearly 85 illustrated in Fig. 5 of the drawings. These said rollers should not be of a diameter greater than the combined length of the arms a^2 and b , whereby the passage of the parcel-carrier B will not be obstructed, and the object of 90 using the beveled rollers E is to leave plenty of room for the passage of said carriers, while at the same time a roller of a large diameter can be used, whereby friction is reduced.

As a means for driving the chain I provide 100 a sprocket-wheel G, which said wheel has two sets of teeth g projected radially from the

periphery thereof. These said teeth are angular in contour and engage with the angular spaces separating the plates *a* from each other. Said wheel *G* is mounted upon a suitable shaft *G'*, which is journaled within boxes *d'* of suitable hangers *D'*. This said wheel, as illustrated in Fig. 2 of the drawings, is located above the receptacles *B*, and it is supplied with an annular groove *g'* for receiving the links *a'*. When the wheel is thus used above the chain, a set of beveled rollers *C* should be at each side thereof for maintaining the chain in engagement with said wheel, as illustrated by dotted lines in Fig. 1 of the drawings.

The driving-wheel is revolved by a suitable pulley *II*, which is mounted on the shaft *G'*. This said pulley is driven by a belt *h*, which may be attached to any suitable driving mechanism.

In Fig. 8 of the drawings I have illustrated the driving-wheel placed beneath the chain, and in this construction said wheel must comprise two separate parts *G²* and *G³*, which said parts are provided with teeth *g*, located directly opposite to each other. These said wheels *G²* and *G³* are mounted upon shafts *I* and *I'*, which are journaled within boxes *d²* of hangers *D⁴*. Mounted upon the shafts *I* and *I'* are gear-wheels *J* and *J'*, which said wheels gear with pinions *K*, which are mounted upon a shaft *L*, which is supported by the hanger *D⁴*. This said shaft *L* is provided with a pulley *II'* for engagement with a belt *h'* for driving the mechanism.

In Fig. 9 of the drawings the arms *a²* of the plates *a* are lengthened to a considerable extent, whereby when the chain takes a vertical position the carriers will not contact therewith. When the chain is passed from one elevation to another upon a slight incline, as illustrated in Fig. 4 of the drawings, it is not necessary to so lengthen the arms *a²*.

In the operation of the device the driving-pulley will be given continuous rotary motion, which motion being communicated to the driving-wheels and thence the chain said chain will be caused to travel continuously, whereby parcels *M* may be placed within the receptacles *B* and carried from any given place to another situated in the line of travel of the chain.

I do not confine myself to the specific details of mere mechanical construction as herein described and shown, as it is obvious that

under the scope of my invention I am entitled to variations of detail.

Having thus described my invention, what I claim as new, and desire to secure by Letters Patent, is—

1. As a means for transmitting parcels, a construction comprising an endless chain composed of a plurality of hexagonal plates and connecting-links therefor, and a plurality of depending receptacles connected to the centers of said plates, and means for supporting and driving the chain, substantially as shown and described.

2. In a parcel-delivery apparatus, the combination of an endless chain composed of hexagonal plates and connecting-links therefor, a plurality of parcel-carrying receptacles suspended centrally from the plates of said chain, friction-rollers for supporting the said chain at each side, grooved rollers for guiding same in a curved direction, and a sprocket-wheel for driving the chain, substantially as shown and described.

3. As a means for transmitting bundles, the combination of an endless chain composed of hexagonal plates and links for connecting said plates, a plurality of suspended carriers which swing upon arms projected from the center of said plates, and means for supporting and guiding the said chain; with a sprocket-wheel comprising two sections which permit the depending arms to pass between them, each section having peripheral angular teeth thereon which are located opposite to each other and which engage the said hexagonal plates on each side for the purpose of driving the chain, substantially as shown and described.

4. In a parcel-delivery apparatus, an endless chain comprising a plurality of hexagonal plates and a plurality of links for connecting said plates to each other, said plates having arms projected centrally therefrom and bundle-carrying receptacles depending from said arms, the chain being adapted for traveling in varying directions, substantially as shown and described.

In testimony that I claim the foregoing as my invention I have signed my name, in presence of two witnesses, this 5th day of June, 1896.

GEORGE E. PANCOAST.
